UNITED STATES PATENT OFFICE.

CLARKE S. DRAKE, OF MILWAUKEE, WISCONSIN.

CIGAR-LIGHTER..

No. 928,252.

Specification of Letters Patent. Patented July 20, 1909.

Application filed January 23, 1909. Serial No. 473,818.

To all whom it may concern:

Be it known that I, CLARKE S. DRAKE, residing in Milwaukee, in the county of Milwaukee and State of Wisconsin, have invented new and useful Improvements in Cigar-Lighters, of which the following is a description, reference being had to the accompanying drawings, which are a part of this specification.

10 This invention has for its object to provide a neat and simple mechanism for automatically igniting to become a flaming torch for lighting cigars and the like.

The invention comprises a torch member 15 with a reservoir containing gasoline or alcohol or other combustible material, preferably fed by means of a wick to the mouth thereof, such torch member being pivotally mounted so as to swing from a position in which its 20 mouth is closed by a stationary member to extinguish the flame and prevent evaporation of the combustible material and in its travel pass close to a terminal of a secondary circuit of an induction coil or other means for 25 producing a jump spark between said terminal and the torch member which preferably constitutes the other terminal of the secondary circuit, there being a switch actuated by the movements of the torch member for 30 controlling the primary circuit of the induction coil to produce the jump spark at the desire time.

With the above and other objects in view the invention consists in the cigar lighter as 35 herein claimed, its parts and combinations of parts and all equivalents.

Referring to the accompanying drawings in which like characters of reference indicate the same parts in the different views; Figure 40 1 is a sectional elevation of a cigar lighter constructed in accordance with this invention with the electrical circuits shown in diagram; and, Fig. 2 is a bottom view thereof.

In these drawings 10 indicates a tubular 45 standard or stationary member which is preferably of metal and is provided with a base 11 by means of which it may be secured to a supporting plate 12 of any material. The movable member is pivotally mounted 50 at 13 to ears of the stationary member 10 and comprises a reservoir 14 with a tubular neck 15 carrying wicks 16 to convey the liquid combustible 17 to the inclined mouth at the end of the neck portion 15, and a handle 18 55 projecting forwardly from the reservoir near the pivotal connection, and a downwardly

extending arm 19 projecting through an opening in the base of the stationary member. The movable torch member is normally held in its upright position with the inclined 60 mouth of the wick tube closely fitting beneath the inclined projection 20 of the stationary member 10 by a coil spring 21 which connects the arm 19 with a bolt 22 on the base 11. The said bolt 22 and another bolt 65 23 serve to fasten an insulating block 24 to the bottom of the base 11 and the bolt 22 extends beyond the insulating block with an insulating sleeve 25 thereon which is engaged by the spring and insulates the spring from 70 the bolt. The spring is also insulated from the arm 19 by having its connection therewith in the form of a pair of strips 26 of insulating material pivotally attached to the opposite sides of the arm at one end and having the wire of the spring passed through their other ends, there being a metal contact roller 27 mounted on the wire of the spring between the insulating strips 26 and riding on the surface of the insulating block 24. A 80 stationary contact 28, preferably in the form of a staple embedded in the surface of the insulating block 24, stands in the path of the contact roller 27 to be engaged thereby at the beginning of the movement of the movable member.

The stationary member 10 is tubular with a bend at its upper end and through it a heavily insulated comparatively large wire 29 passes with its end bared of insulation 90 and entered into an insulating plug 30 of fiber or other insulating material, the opening through said plug being of such shape that it permits the insulation of wire 29 to enter therein to an extent which will insure 95 the proper insulation of the bared end of the wire from the stationary member 10. The insulating plug has a tight fit in the open end of the stationary member and the bared end of the wire 29 is bent downwardly 100 at the end of the plug and terminates at a point where it will stand close to the path of the upper end of the movable member as it swings outwardly from its closed position, the parts being so positioned with relation 105 to each other that the upper end of the movable member is close to the end of wire 29 at the time the contact roller 27 engages the stationary contact 28.

The engagement of the contact roller 27 110 with the stationary contact 28 is made to constitute a switch for the primary circuit

of an induction coil, the stationary contact 28 being connected by a wire 31 with the primary winding of the induction coil 32, which includes the vibrator 33 as usual, and 5 a wire 34 connecting the other terminal of the primary winding with one terminal of a battery 35, while the other terminal thereof is connected by a wire 36 with the spring 21 which supports the roller. The wire 29 10 connects with the secondary winding of the induction coil 32 which is also connected by a wire 37 to a binding post 38 connecting the base of the stationary member to the supporting plate 12.

15 The return movement of the movable member is limited by the engagement of a set screw 39 threaded through the arm 19 with the end of the insulating block 24 which cushions the blow and avoids the 20 striking of the metal parts.

In operation, the parts are moved from their normal position by pressing on the handle 18 to swing the torch member away from the stationary member and against the 25 action of spring 21. In so doing the contact roller 21 is moved into engagement with the stationary contact 28 to close the primary circuit of the induction coil and set the vibrator 33 thereof in action, the 30 primary circuit extending from the battery 35, through wire 36 and spring 21 to the contact roller 27, and from the stationary contact 28, engaged thereby, through the wire 31 and the primary winding of the induction coil 32, including the vibrator 33, back to the battery by way of wire 34. The induced current of the secondary winding of the induction coil traverses the secondary circuit from the secondary winding of the 35 induction coil, through wire 29, leaping the air gap between the bent end of wire 29 and the mouth of the wick tube 15 which is then beneath it, for the pivotal mounting of the movable member on the stationary member 40 45 50 55 60

10 places it in electrical connection therewith, then returning through wire 37 to the induction coil. The jump-spark thus produced at the mouth of the wick tube at the beginning of its outward movement continues during a portion only of said movement, as long as the contact roller remains in engagement with the stationary contact 28, and ignites the wick to form a flaming torch of the movable member by means of which cigars and the like may be lighted; and upon the release of handle 18 spring 21 returns the torch member to its upright position extinguishing the flame by fitting its mouth beneath the inclined projection 20 of the stationary member.

It will be noted that the operative parts are mounted on the base of the stationary member so that they may be assembled before mounting the stationary member on the supporting plate 12, which is an advan-

tage when the supporting plate 12 constitutes a polished wood casing or is of other material liable to be marred. Furthermore this arrangement of the operative parts permits the stationary member to be mounted on a metal supporting plate without interfering with the circuits.

It is to be understood that the primary and secondary circuits of the induction coil include all of the necessary parts to their proper operation and it is with this understanding that they are referred to as such in the claims for convenience of expression.

What I claim as my invention is:

1. A cigar lighter, comprising a stationary member and a movable member, a combustible material carried by one of the members, an induction coil, a switch for the primary circuit of the induction coil operated by the movements of the movable member, one of the terminals of the secondary circuit of the induction coil being connected to one of the members, and an insulated conductor forming the other terminal of the secondary circuit of the induction coil on the other member to form a spark gap in proximity to the combustible material at the time of closing the switch.

2. A cigar lighter, comprising a stationary member and a movable member, a reservoir for combustible material carried by one of the members, a wick for leading the combustible material to the mouth of the reservoir which is closed by the other member in the normal position of the parts, an induction coil, a switch for the primary circuit of the induction coil operated by the movements of the movable member, and means for producing a spark gap in the secondary circuit of the induction coil at the mouth of the receptacle for combustible material at the time of closing the switch.

3. A cigar lighter, comprising a stationary member, a movable member pivotally mounted thereon and comprising a reservoir for combustible material with a tubular neck portion normally closed by fitting against the stationary member, means for holding the movable member in its normally closed position, an induction coil, a switch for the primary circuit of the induction coil operated by the movements of the movable member, and an insulated conductor of the secondary circuit of the induction coil having its bared terminal standing in a position close to the path of the neck of the receptacle for combustible material to form a spark gap therewith at the time of closing the switch.

4. A cigar lighter, comprising a stationary member, a movable member pivotally mounted thereon and comprising a reservoir for combustible material with a tubular neck portion normally closed by fitting against the stationary member, means for holding the movable member in its normally closed posi-

tion, an induction coil, a switch for the primary circuit of the induction coil operated by the movements of the movable member, an insulated conductor of the secondary circuit of the induction coil passing through the stationary member and having its end bared 5 of insulation, and an insulating plug fitting in the stationary member with the bared end of the insulated conductor fitting therein and 10 projecting therefrom at a distance from the stationary member and bent at an angle to stand close to the path of the neck of the receptacle for combustible material to form a spark gap therewith at the time of closing the 15 switch.

5. A cigar lighter, comprising a stationary member mounted on a base, a movable member pivotally mounted thereon and comprising a reservoir for combustible material with 20 a tubular neck portion with an inclined end normally closed by fitting against an inclined projection of the stationary member, an arm projecting from the movable member through the base of the stationary member, 25 a spring connected with said arm for holding the movable member normally in its closed position, an induction coil, a switch for the primary circuit of the induction coil mounted on the base of the stationary member and 30 operated by the movements of the arm, and an insulated conductor of the secondary circuit of the induction coil extending through the stationary member and terminating in a 35 position to form a spark gap with the neck of the reservoir of the movable member at the time the switch is closed.

6. A cigar lighter, comprising a stationary member mounted on a base, a movable member pivotally mounted on the stationary member and consisting of a reservoir for combustible material having a tubular neck portion, an arm on the movable member projecting through the base of the stationary member, an insulating block beneath the 45 base of the stationary member, an induction coil, a stationary contact on the insulating block forming one terminal of the primary circuit of the induction coil, a roller contact carried by the arm and forming the other 50 terminal of the primary circuit of the induction coil, means for normally holding the movable member in a position in which the

contacts of the primary circuit are out of engagement, an insulated conductor of the secondary circuit of the induction coil passing through the stationary member with its terminal close to the path of movement of the neck of the reservoir for combustible material to form a spark gap therewith at the time the contacts of the primary circuit are 60 engaged.

7. A cigar lighter, comprising a stationary member mounted on a base, a movable member pivotally connected with the stationary member and constituting a reservoir for a 65 combustible material with a tubular neck having an inclined mouth, an inclined projection on the stationary member for closing the mouth of the reservoir neck in the normal position of the movable member, a handle projecting from the movable member for moving the same, an arm projecting from the movable member through the base of the stationary member, an insulating block secured to the under side of the base of the stationary member, an induction coil, a staple embedded in the insulating block and forming a stationary contact of the primary circuit of the induction coil, an insulating post on the insulating block, a coil spring mounted 80 thereon, insulating strips connecting the coil spring with the arm of the movable member, a contact roller mounted on the end of the spring between the insulating strips and bearing on the insulating block and forming 85 a movable contact of the primary circuit of the induction coil to engage the stationary contact and close the primary circuit of the induction coil during the movement of the movable member, and an insulated conductor of the secondary circuit of the induction coil passing through the stationary member and having its bared terminal standing near the path of movement of the neck of the reservoir for combustible material to form a 95 spark gap therewith at the time of engagement of the contacts of the primary circuit.

In testimony whereof, I affix my signature, in presence of two witnesses.
